CAR TRAY

John L. Jennings, 404 Amber Way, Hanford, Calif.

Filed Oct. 7, 1963, Ser. No. 76,895

Term of patent 14 years

(Cl. D14—6)

FIG. 1 is a side elevation of a car tray showing my new design.

FIG. 2 is an end elevation of the car tray of FIG. 1.

FIG. 3 is a top plan view of the car tray.

FIG. 4 is a bottom plan view of the car tray.

FIG. 5 is a perspective view of the car tray.

The broken lines shown in FIGS. 1, 3 and 5 are included for illustrative purpose only.

I claim:

The ornamental design for a car tray, as shown and described.
